(57) **CLAIM**

The ornamental design for a tent lock, as shown and described.

DESCRIPTION

FIG. 1 is a top perspective view of a tent lock showing my new design;

FIG. 2 is a front view thereof, a rear view being a mirror image of the front view;

FIG. 3 is a left side view thereof, a right side view being a mirror image of the left side view;

FIG. 4 is a top view thereof;

FIG. 5 is a bottom view thereof;

FIG. 6 is a bottom perspective view thereof;

FIG. 7 is an exploded view thereof; and,

FIG. 8 is a perspective view thereof in a used configuration. The broken lines in FIG. 8 are for the purpose of illustrating the environmental structure and form no part of the claimed design.

1 Claim, 8 Drawing Sheets
